DESIGN FOR A SUN MASK

Joanna Maria Higersberger, New York, N. Y.

Application January 24, 1941, Serial No. 98,343

Term of patent 3½ years

To all whom it may concern:

Be it known that I, Joanna Maria Higersberger, a citizen of the Republic of Poland, residing in New York, New York, have invented a new, original, and ornamental Design for a Sun Mask, of which the following is a specification, reference being had to the accompanying drawing, forming a part hereof.

Fig. 1 is a front perspective view of a sun mask showing my new design.

Fig. 2 is a top view thereof.

Fig. 3 is a perspective view thereof.

Fig. 4 is a side view thereof.

The head band shown in broken lines in Fig. 1 has been omitted from the disclosures in Figs. 2, 3 and 4 for convenience of illustration.

I claim:

The ornamental design for a sun mask, as shown and described.

JOANNA MARIA HIGERSBERGER,
